UNITED STATES PATENT OFFICE.

GUSTAVE VAN DE VEIRE, OF WATERTOWN, MASSACHUSETTS.

PROTRACTOR.

Application filed September 25, 1922. Serial No. 590,348.

To all whom it may concern:

Be it known that I, GUSTAVE VAN DE VEIRE, a citizen of the United States, residing in Watertown, in the county of Middlesex and State of Massachusetts, have invented an Improvement in Protractors, of which the following is a specification.

This invention relates to and has for its object to provide a protractor adapted for 10 use especially by both draftsmen and machinists and arranged to give both obtuse and acute angles on opposite sides thereof.

A further object is to provide a protractor and attachments therefor by which the 15 protractor may be supported in a vertical position for the laying out and measurement of vertical angles.

A further object is generally to improve the construction and extend and facilitate 20 the use of protractors.

Fig. 1 is a plan view of a protractor embodying the invention.

Fig. 2 is a side elevation, in detail, of 25 Fig. 1.

Fig. 3 is a plan view of the protractor with the blade at the outer edge of the base plate.

Fig. 4 is a plan view illustrating more 30 particularly an attachment secured to an edge of the base plate by which the protractor may be supported in a vertical position.

Fig. 5 illustrates, in side elevation, a protractor having attachments by which it may be supported above a base plane for the 35 measurement of angles, the sides of which do not coincide with a side of the base plate of the protractor.

Fig. 6 is an end view of Fig. 5.

Fig. 7 is a sectional elevation along line 40 7-7 of Fig. 5.

Fig. 8 is a sectional detail through the rotatable disc, taken along line 8-8 of Fig. 1, and illustrating the clamping means for the adjustable blade.

Fig. 9 is a sectional detail through the clamping means of the attaching-member taken along line 9-9 of Fig. 1.

As here shown, the protractor embodying my invention includes a flat base-plate 10 having parallel opposed side edges 11 and the end edge 12 arranged at right angles to said side edges. Said plate is also formed with the openings 13 and 14 the side walls of which are or may be substantially parallel to the corresponding edges 11 and 12 of

the plate. That end-portion of said plate opposite the edge 12 is or may be of more or less circular formation and is provided with a circle of degree graduations 15 which start from 0° at the opposite side edges of the plate and terminate at 90° in a line parallel to the side edges of the plate.

A stud 16, Fig. 7, is secured to said plate 10 at the center of said circle of graduations and extends thereabove to support a rotatable disc 17. Said stud includes an end-portion 16^a which is driven into an aperture of said plate 10 and is, in effect, integral or rigid with said plate. Said stud is formed with an enlarged cylindrical bearing member or hub 16^b which is adapted to support said disc 17 rotatably and, for this purpose, said disc may be formed with a recess 18 in its under face in which said hub 16^b is received. The depth of said recess is adapted to be slightly less than the height of said hub whereby the disc is clear of the base-plate and is supported upon the top flat face of said hub. The side wall of said hub and recess are adapted to be a good fit whereby the disc may be accurately supported rotatably against lateral displacement. Said stud is or may be also formed or provided with a reduced cylindrical extension 16^c which projects through and is a rotatable fit in an aperture in said disc 17. Said stud is also formed with a threaded upper end-portion 16^d on which a thumb nut 19 is received and said nut serves to clamp said disc in fixed position to the base plate 10 or release it for rotary movement thereon. A washer 20 may be interposed between said disc and thumb nut and said washer may be locked against rotation on said stud, if desired, in any suitable manner not necessarily shown.

The periphery of said rotatable disc 17 is or may be beveled to provide a relatively thin lower edge adapted to pass adjacent the degree graduations carried by said base-plate 10, and a vernier 21 may be carried by said disc at its periphery and cooperate with said degree graduations to permit the reading of angles to within less than one degree.

Said disc is or may be formed or provided with an extension 22 opposite said vernier 21 and said extension may be recessed to provide a seat 23, Fig. 8, for an adjustable blade; and said seat is or may be arranged to be perpendicular to a line passed through

the center of said stud 16 and the center of the vernier. A blade 24 is adapted to be received in the recess in said disc-extension and above the base-plate. Said blade may 5 be provided with a slot 25 extended from end to end of it and a clamping member 26 is adapted to enter said slot and serves to clamp said blade in adjusted position to said disc 17.

10 An eccentric clamping lever 27 may actuate said clamping member in a more or less customary manner.

Said disc 17 with its blade 24 is adapted to rotate throughout a complete circle and 15 angles may be laid out and measured with the blade 24 in a position between the pivot stud 16 of the disc and the body of the base plate, as illustrated in Fig. 1, and also when the blade is in a position beyond the pivot 20 stud and the body of the base plate, as illustrated in Fig. 3.

When the protractor, as so far described, is used, by draftsmen, for instance, to lay off angles on a surface, the blade 24 is 25 raised above the surface by a distance at least equal to the thickness of the base plate, and thereby prevents the accurate drawing of lines inasmuch as there is no barrier to prevent the point of the pencil, or equivalent, from being moved unintentionally under the blade. In other words, the pencil can not be guided accurately unless the blade is in direct contact with the paper or other surface on which the line is to be traced.

30 In accordance with an object of my invention, I provide means which operates, in effect, to extend the edge of the blade 24 to the lower face of the base plate, whereby to close the gap between the blade and a surface on which the protractor may be placed. Said means includes an attaching member 28, Figs. 1, 2 and 9 which has a flat face 29 of 35 substantial width. Said member is or may be formed with a groove 28^a in which the edge of said blade 24 is adapted to be received and said member may be provided with a clamping-member 29^a which is adapted to engage the opposite edge of said blade, whereby to clamp said attaching-member 40 in adjusted position on said blade. Said clamping member may be actuated by means including the thumb nut 29^b in any suitable manner. Said attaching member is or may be formed with the bevelled end portion 28^b 45

50 whereby said member may be moved directly in contact with an edge of the base-plate and provide a definite boundary for the angle included between the edge of said base-plate and the face of the attaching member. The face of said attaching-member is adapted to depend below the blade 24 and be substantially flush with the lower 55 face of the base plate.

Said attaching-member 28 is also adapted 60 to be clamped removably to the edges 11 and 65

12 of the base-plate, as illustrated in Figs. 1 and 4, and the flat face 29 thereof provides a substantial support on which the protractor may rest for the laying out and measurement of vertical angles.

70

With the usual type of protractor it is sometimes difficult to measure or lay out angles when the body of the protractor must be held in a fixed position, as is often the case. In accordance with my invention, 75 I provide means to accomplish this result. Said means includes a blade 30, Fig. 5, having a straight edge 31. Said blade is pivoted to one end of a link 32 and may be clamped in adjusted position thereto by 80 means including the clamping nut 33. The other end of said link is pivoted to a supporting member 34 and may be clamped in adjusted position by suitable means including the clamping nut 35. Said supporting member 34 is adapted to be secured adjustably to an edge of the base-plate of the protractor by suitable means including the clamping nut 36. Said blade 30 is 85 adapted to function in cooperation with the blade 24 for the laying out and measurement of angles in a manner which may be readily understood.

90

95 For many purposes it may be desirable to support the protractor in a vertical position at a substantial distance above a supporting surface. For this purpose, I may provide a standard which includes the base block 40, which latter may have the V-shaped groove 41 therein by which the block may engage round or V-shaped supporting members, and the flat surfaces 42 by which the block may be supported on a plane surface. A cylindrical rod 43 may be secured to and 100 extend perpendicularly above said block and may be provided with a vertically-adjustable supporting member 44 adapted to hold the protractor.

105

105 Said supporting member may include a clamping screw 45 by which said member may be secured in adjusted position on said rod, and an arm 46 which bears a lateral projection 47 having a clamping nut 49. Said projection is adapted to enter holes 48, Fig. 1, formed in the base plate of the protractor and secure it to the supporting member. Said arm 46 of the supporting member is or may be formed with an extension 50 in which an adjusting screw 51 is threaded and said screw is adapted to bear 110 against an inner edge of the protractor base-plate and move it into a desirable position, in which position the protractor may be secured by the nut 49.

115

115 I claim:

120 1. A protractor having a base-plate formed with parallel side-edges and an end-edge arranged at right angles to said side-edges and slots having edges arranged substantially parallel to said side and end-edges,

125

130

a disc pivotally supported on said base-plate and rotatable throughout a complete revolution over a face of said base-plate, a blade carried by said disc, and co-registering degree indicia carried by said disc and base-plate.

2. A protractor having a base-plate, a disc pivotally supported on said base-plate and rotatable over the upper face of said base-plate, and a blade carried by said disc and movable therewith over the upper face of and adapted to extend laterally beyond said base-plate, said blade having a depending extension adapted to extend said blade substantially to the lower face of said base-plate.

3. A protractor having a base-plate, a disc pivotally supported on said base-plate and rotatable over the upper face of said base-plate, and a blade carried by said disc and movable therewith over the upper face of and adapted to extend laterally beyond said base-plate, said blade having an adjustable depending extension adapted to extend the edge of said blade substantially to the lower face of said base-plate.

4. A protractor having a base-plate, a disc pivotally supported on said base-plate and rotatable over the upper face thereof, a blade carried by said disc and movable therewith over the upper face of said base-plate, and an attaching-member adapted to be secured adjustably to said blade having a straight face of substantial length which is arranged to extend below said blade and terminate substantially in the plane of the lower face of said base-plate.

5. A protractor having a base-plate formed with a relatively thin edge-face, a disc pivoted on said base-plate, a relatively thin blade adjustably connected to said disc, and a member having a relatively broad edge-face adapted to be secured to the edge of said base-plate and also to the edge of said blade.

6. A protractor having a base plate, a

disc pivotally mounted on the upper face of said plate, a blade carried adjustably by said disc and having an extension arranged to extend substantially flush with the lower face of said plate, a supporting member having means connecting it with said plate for adjustment along the length thereof, and a second blade pivotally connected to said supporting member having an end thereof arranged to extend over the side edge of and engage said base plate and also said first blade.

7. A protractor having a base-plate, a disc pivotally carried by said base-plate, a blade carried by said disc and adapted to extend laterally of said base-plate, a second blade adapted to cooperate with said first blade, a link pivoted to said second blade, and a supporting member to which said link is pivoted having means for detachable connection with said base-plate.

8. A protractor having a base-plate, a disc pivotally carried by said base-plate, a blade carried by said disc and adapted to extend laterally of said base-plate, a second blade adapted to cooperate with said first blade, a link pivoted to said second blade, and a supporting member to which said link is pivoted having means for detachable connection with said base-plate, and means to clamp said second blade in angularly adjusted positions relative to said base-plate.

9. A protractor having a base-plate, a disc pivotally carried by said base-plate, a blade carried by said disc and adapted to extend laterally of said base-plate, a second blade adapted to cooperate with said first blade, a supporting member pivotally connected with said second blade, means detachably to secure said supporting member to said base-plate, and means to clamp said second blade and supporting member against relative movement.

In testimony whereof, I have signed my name to this specification.

GUSTAVE VAN DE VEIRE.
